UNITED STATES PATENT OFFICE

115,332

DESIGN FOR A PICTURE EXHIBITING MEDALLION

Birchall Hammer, Elkins Park, Pa.

Application October 7, 1938, Serial No. 80,299

Term of patent 7 years

To all whom it may concern:

Be it known that I, Birchall Hammer, a citizen of the United States, residing at Elkins Park, in the county of Montgomery and State of Pennsylvania, have invented a new, original, and ornamental Design for a Picture Exhibiting Medallion, of which the following is a specification, reference being had to the accompanying drawing, forming part thereof, in which,

Fig. 1 is a view in front elevation of a picture exhibiting medallion embodying my new design, and

Fig. 2 is a transverse section thereof on the lines 2—2 in Fig. 1.

I claim:

The ornamental design for a picture exhibiting medallion, substantially as shown.

BIRCHALL HAMMER.
